CONDENSATE HANDLING APPARATUS

Walter C. Greene, Cleveland Heights, Ohio

Application December 30, 1931, Serial No. 583,897

12 Claims. (Cl. 237—67)

This invention relates to heating apparatus of the type utilizing both high and low steam pressure, with an air pump for producing a suction or vacuum effect and a water pump for handling the liquid condensate.

One object of the invention is to provide a cross connection between the high and low pressure parts of the system, together with control means therefor, arranged in such manner that in starting the system the vacuum effect applied to the low pressure return line is also made effective in the high pressure return line, to quickly remove air or vapor and expedite the distribution of heating steam, but which is rendered ineffective therein when the high pressure return line comes up to operating temperature.

A further object of the invention is to provide an improved arrangement in which priming liquid for the air pump is constantly supplied to it at relatively low temperature from a low temperature part of the high pressure condensate reservoir, to constantly maintain the pump effective in operation.

A further object of the invention is to provide apparatus of this kind in which a full supply of water is maintained and constantly cooled in the high pressure condensate reservoir, by direct delivery from the water pump, for the purpose of always insuring sufficient cool priming liquid for the air pump.

A further object of the invention is to provide an arrangement in which the water pump discharges condensate directly to the boiler, but not hot condensate, due to constant mixture of the condensates from both high and low pressure return lines and the venting to atmosphere of the high pressure condensate reservoir with accompanying drop in condensate temperature therein, and wherein, furthermore, all air or vapor in the water pump supply is taken off by the air pump in advance of delivery of such water supplied to the water pump.

The foregoing and other features of the invention will be brought out in the following description, drawing and claims.

In the drawing, the figure illustrates a heating system or plant with the condensate handling apparatus applied thereto and in an enlarged arrangement to clearly illustrate the invention.

Referring to the drawing, 1 represent a suitable boiler having a return line 2 and a steam line 3. At the point 4 the steam line branches and one arm enters a reducing valve 5 connected to a low pressure steam line 6 in turn connected

to a plurality of heat radiating devices, such as radiators, for heating purposes. There is an inlet connection and supply valve assembly 7 for each radiator and a thermostatic return trap 8, the thermostatic traps being connected to the low pressure return line 9.

Beyond the connection 4 the other high pressure steam branch or arm 10 leads to such heat radiating devices as a cooker, generally indicated at 11, and a blast coil, generally indicated at 12. All of these devices are provided with their own traps 13 and all traps are connected to the high pressure return line 14.

Mounted at any suitable point, preferably below the water level in the boiler, is a pump casting containing both air and water pump units or members on a pump shaft 16 adapted to be driven by a motor 17. This shaft carries an air rotor 18 of any preferred type adapted to produce a vacuum or suction effect by drawing air through the opening 19 into the chamber in housing 15 and discharging it through the opening 20. The pump shaft also carries an impeller 21 adapted to draw water through the pipe 22 into the chamber in housing 20 and to discharge it through the conduit 23 into the return line 2.

While many of the advantages of my invention may be realized by the use of any efficient vacuum pump adapted to cause the desired effect ascribed to air rotor 18, other advantages are realized only if a certain type of air pump is used. The pump illustrated in the drawing comprises a rotor in hydraulic balance revolving freely in an elliptical casing containing water. The water turns with the rotor and follows the casing impelled by centrifugal force. As the water alternately recedes from and is forced back into the rotor, it draws in air through suitably located inlet ports and discharges it again through other outlet ports. Such a pump discharges small amounts of water which should be returned to the system or the loss becomes considerable over an extended period. Also, such a pump should be continuously primed with relatively cool water for the duty outlined herein.

Mounted above the pump casing is a tank 24 forming a high pressure condensate reservoir having a main compartment 25 and an auxiliary high pressure return compartment 26, the two being formed by a vertical wall or partition 27 extending up from the bottom of the tank to a point near the top, thereby leaving an opening above the partition. This tank is connected by a manifold structure with the air pump. The manifold structure includes a conduit 28 leading

to the pump inlet port 19 and another conduit 29 communicating with the top of the water chamber of the water pump, as at 30. These two conduits 28 and 29 extend upwardly side by side and are cross connected at the top where they communicate with a pipe 31 leading to the low pressure condensate reservoir to be described.

In addition to the conduits already described, the manifold referred to includes a conduit 33 10 which leads from the air exhaust port 20 of the air or vacuum pump and communicates by a connection 34 with the vapor space in the top of the tank 24. A check valve 34' is provided in the connection 34 to prevent return flow from 15 the tank to the air pump.

The tank 24 is preferably provided with an air relief or vent 35 placed above the high pressure return compartment 26 and which vents any air and steam which may accumulate in the 20 top of the tank. This open vent also promptly reduces the temperature of any condensate which reaches the tank at temperatures above boiling. The vapor portion of the tank is connected to a suitable strainer 36 in the high pressure return pipe. Spaced above the bottom of 25 the high pressure condensate compartment 26 is a cross partition or wall 37 having a valve seat 38 therein adapted to receive a valve 39 carried by a float 40. When the water accumulates sufficiently in the compartment 26, the float valve 30 rises and discharges some of the water therein into the low pressure reservoir.

Connected to the water supply pipe 22 for the water pump, is a casing 41 containing a check 35 valve 42 closing toward the low pressure condensate reservoir 43. This check valve 41 is connected to the side of the low pressure condensate reservoir and communicates therewith through a strainer 45 in chamber 44. The upper 40 portion of reservoir 43 is connected to the pipe 31 and its chamber communicates with a drain pipe 46 coming from the bottom of the high pressure condensate compartment 26 in reservoir 25 below the float valve 39. The low pressure condensate reservoir 43 also communicates 45 with a pipe 47 leading down to a connection 48 at the lower end of the low pressure return line 9. In the low pressure condensate reservoir is 50 a float 49 pivoted at 50 and arranged to actuate an arm 60 on the outside of the casing and connected to a switch (not shown) in the operating electrical circuit to the motor 17, so that starting 55 and stopping of the motor is automatically controlled in accordance with the level of liquid in the low pressure condensate reservoir 43. With a sufficient accumulation of condensate in reservoir 43 the motor starts automatically and the two pump elements are operated and the condensate is pumped back to the boiler. At the same time, 60 the air pump produces a vacuum effect which is applied by conduit 29 to the chamber within the water pump casing and by pipe 31 to the vapor space in the low pressure condensate reservoir, as well as to the low pressure return line.

65 When a system of this kind is started, or when it is cold and the necessity arises to bring it up to full operating condition, there is frequently a very material lag in the sweep of the high pressure steam to all parts of the high pressure portion of the system. The action may be expedited by applying a vacuum effect to the high pressure return line. For this purpose I supply a cross connection between the low pressure and high pressure return lines, consisting 70 of a pipe 62 connected at one end to the low

5 pressure return line, as to the pipe 47, and which at its other end communicates with a thermostatic trap 63, the latter in turn connected by a pipe 64 to the high pressure return line 14. A check valve 64' is preferably also located in the return line 14 between the cross connection and reservoir 25, so that the vacuum effect is not transmitted to reservoir 25. With this arrangement, in starting or when the system is cold and is being brought up to operating condition, the thermostatic trap is open and the vacuum effect produced in reservoir 43 is communicated to the return end of the high pressure part of the system, evacuating air therefrom and when the steam or returned condensate reaches the thermostatic trap and heats it to the proper temperature, said trap closes and cuts off the vacuum effect, so that the high pressure part of the system thereafter operates with high pressure steam.

20 In the arrangement described, when the condensate from the high pressure return line 14 reaches reservoir 24 its temperature is immediately reduced to boiling by evacuation through the open vent 35 to atmosphere of excess steam 25 or vapor which would normally interfere with 30 operation of the air pump. As condensate accumulates in tank 24 it fills the larger compartment 25 and when a sufficient accumulation occurs in compartment 26 the float valve rises 35 and a portion of the liquid drains by gravity to the low pressure condensate reservoir 43 from which it is eventually pumped back to the boiler. The larger compartment 25 is maintained full and the condensate therein gradually cools by 40 radiation, the cooler portion lying at the bottom, from which a drain pipe 70 conducts a supply of cool priming liquid to the chamber of the air pump, as shown in the drawing. This provides at all times a constant available supply 45 of priming liquid so that efficient and satisfactory operation of the air pump is assured at all times and loss of priming liquid is immaterial. Furthermore, the hot condensate in reservoir 26, even though at boiling temperature, is mixed 50 with cooler condensate in reservoir 43 before going to the boiler. The cooler condensate has a temperature of approximately 150° and the mixture therefore goes to the boiler at a temperature materially below boiling and with no liability of flashing and interfering with operation of the air pump.

55 Means is also provided for insuring at all times a full supply of liquid in process of being cooled in the large chamber 25 of the high pressure condensate reservoir, to which the cooler liquid handled by the water pump is directly delivered by way of a pipe 65 including a cooling coil 66 and an adjustable valve 67 by which the quantity flowing may be varied as desired. This valve may be partially opened so as to permit a constant flow at all times when the water pump is operating and the quantity may be just sufficient to keep the chamber 25 full or, if desired, valve 67 may be opened wider and the excess water delivered to compartment 25 and cooled by its passage through the cooling coil 66 will over-flow into compartment 26, mix with the hot liquid therein and ultimately be returned to reservoir 43.

60 Having described my invention, I claim:

65 1. Heating apparatus, comprising a boiler, a plurality of steam lines connected thereto, means 70

for establishing relatively high and low pressures in said lines, heat utilizing devices communicating with said lines, high and low pressure return lines connected respectively there-

- 5 with, a separate condensate reservoir for each of said return lines, liquid pump means for returning the condensate to the boiler, air pump means employing priming liquid for creating vacuum in the low pressure return line, means
- 10 for dissipating steam or vapor from the high pressure condensate reservoir, means for delivering excess condensate from the high pressure condensate reservoir to the low pressure condensate reservoir while preventing air passage
- 15 between the reservoirs, and a liquid priming connection from one of said condensate reservoirs to the air pump chamber.

2. Heating apparatus, comprising a boiler, a plurality of steam lines connected thereto, means for establishing relatively high and low pressures in said lines, heat utilizing devices communicating with said lines, high and low pressure return lines connected respectively with the high and low pressure heat utilizing devices, a separate condensate reservoir for each of said return lines, pump means connected to the low pressure condensate reservoir for returning the condensate therefrom to the boiler and for at the same time creating a vacuum in the low pressure return lines, a steam and air vent for the steam and air space of the high pressure return reservoir, and means for delivering the condensate from said high pressure condensate reservoir to the low pressure condensate reservoir while preventing air passage between the reservoirs.

3. Heating apparatus, comprising a boiler, high and low pressure steam and return lines communicating therewith, heat utilizing devices connected between said steam and return lines, a condensate reservoir communicating with the high pressure return line, a condensate reservoir communicating with the low pressure return line, vacuum producing and liquid pump means connected to the low pressure condensate reservoir and arranged to deliver condensate therefrom to a boiler and at the same time to create a vacuum effect in the low pressure condensate reservoir and return line, means for venting pressure from the high pressure condensate reservoir, and means for periodically delivering the accumulating condensate in the high pressure condensate reservoir to the low pressure condensate reservoir.

4. Heating apparatus of the character described in claim 3, including a vacuum producing pump means employing priming liquid, and a priming liquid supply line for conducting a cooled liquid from a low temperature point in the high pressure condensate reservoir to the vacuum producing portion of said pump means.

5. Heating apparatus, comprising a boiler, a plurality of steam lines connected thereto, means for establishing relatively high and low pressures in said lines, heat utilizing devices communicating with said lines, high and low pressure return lines connected respectively with the high and low pressure heat utilizing devices, a separate condensate reservoir for each of said return lines, vacuum producing and liquid pump means connected to the low pressure condensate reservoir for returning the condensate therefrom to the boiler and for creating a vacuum effect in the low pressure return line, a steam

high pressure condensate reservoir, a drainage connection from the high pressure condensate reservoir to the low pressure condensate reservoir arranged to prevent the passage of air between reservoirs, and means for rendering the vacuum effect which is normally effective in the low pressure return line effective in the high pressure return line during starting of the apparatus.

6. Apparatus of the character described in claim 5, in which said last named means is thermostatically operated and is sensitive to the temperature of the high pressure return line, whereby the vacuum effect of the low pressure return line is cut off from the high pressure return line when the latter reaches operating temperature.

7. Heating apparatus, comprising a boiler, a plurality of steam lines communicating with said boiler, means for establishing relatively high and low pressures in said lines, heat utilizing devices communicating with said high and low pressure steam lines, high and low pressure return lines connected with the high and low pressure heat utilizing devices, condensate collecting means for the low pressure return line, liquid and air pump means for simultaneously returning the condensate to the boiler and for creating a vacuum effect in the low pressure return line, and a reservoir communicating with the high pressure return line and open to atmosphere and having its vapor space communicating with the discharge side of the air pump means and with the low pressure return line and arranged to deliver its excess water accumulation into said collecting means while preventing the delivery of air thereto.

8. Heating apparatus of the character described in claim 7, including means for delivering water from the liquid pump means directly to said reservoir.

9. Heating apparatus of the character described in claim 7, including air pump means employing a priming liquid, means for delivering water from the liquid pump means directly to said reservoir, and a drainage connection from a low temperature point in said reservoir to the chamber of the air pump means for conducting priming liquid thereto.

10. Heating apparatus, comprising a boiler, a plurality of steam lines communicating therewith, means for establishing relatively high and low pressures in said lines, heat utilizing devices connected to said high and low pressure steam lines, high and low pressure return lines connected respectively with the high and low pressure heat utilizing devices, condensate collecting means for the low pressure return line, a condensate reservoir for the high pressure return line, a drainage connection therefrom to the low pressure condensate reservoir arranged to prevent the passage of air between reservoirs, liquid and air pump means for simultaneously returning condensate to the boiler and for creating a vacuum effect in the low pressure condensate reservoir and return line, means for conducting cooled liquid from said liquid pump means to the high pressure condensate reservoir, and a vent to atmosphere for said high pressure condensate reservoir.

11. Apparatus of the character described in claim 10, including a cross connection between the high and low pressure return lines for rendering the vacuum effect in the latter effective in the former, and thermostatic means sensi-

tive to the temperature of said high pressure return line for opening said connection when the high pressure return line is cold.

12. Heating apparatus, comprising a boiler, a plurality of steam lines connected thereto, means for establishing relatively high and low pressures in said lines, heat utilizing devices communicating with said lines, high and low pressure return lines connected respectively with the high and low pressure heat utilizing devices, a 5 separate condensate reservoir for each of said return lines, liquid pump means for returning the condensate from the low pressure conden-

sate reservoir to the boiler, a drainage connection from the high pressure condensate reservoir to the low pressure condensate reservoir arranged to prevent the passage of air between reservoirs, and an air pump communicating on its suction side with the low pressure condensate reservoir and return line and with the upper portion of the chamber of the liquid pump means and on its discharge side with the vapor space of the high pressure condensate reservoir, and a vent to atmosphere from the vapor space of the high pressure condensate reservoir. 5 10

WALTER C. GREENE.
